Attorney

UNITED STATES PATENT OFFICE.

ADELBERT A. DURKEE, OF STONEHAM, MASSACHUSETTS.

SHOE FORMER.

Application filed April 18, 1922. Serial No. 555,318.

To all whom it may concern:

Be it known that I, ADELBERT A. DURKEE, a subject of the United Kingdom of Great Britain and Ireland, residing at Stoneham, in the county of Middlesex and State of Massachusetts, have invented a new and useful Improvement in Shoe Formers, of which the following is a specification, reference being had therein to the accompanying 10 drawings.

My invention relates to a shoe former, adapted to be placed in the shoe after the last has been removed, in order to maintain the shoe in its proper form during the final 15 operations of manufacture.

In shoe manufacturing, after the last has been pulled from the shoe, the latter is subjected to a number of final operations such as monogramming, cleaning, the insertion of 20 sock lining, treeing, repairing, dressing, brushing, etc., which operations are usually carried on in the treeing and packing room. These various operations have a tendency to change the form given to the shoe by the last 25 and to destroy its correct lines and fitting qualities. For instance, the natural reaction of the stock under the finishing processes, especially in a thin-soled shoe, frequently causes the toe of the shoe to turn upwardly, 30 which result is aggravated by the monogramming and cleaning processes. This spoils the shape and appearance of the shoe. Again, it frequently happens in shoes made 35 from soft leathers that small wrinkles appear in the leather, owing to the fact that it is not supported over a firm substance or held under tension during the final processes. It is customary to shrink out these wrinkles with a hot iron which, however, shrinks the 40 leather without affecting the lining, and thereby causes an objectionable fullness in the latter. In short, these various final processes have the general effect of distorting 45 the shoe and destroying the correct form given it by the last, so that, when the shoe is packed, its sides are spread apart more or less, giving it an appearance of having been worn and detracting from its attractiveness.

The main object of my invention is the 50 provision of a shoe former, adapted to hold the shoe under a longitudinal tension during the final manufacturing processes, in order that it may have a correct form when finished and ready for the market.

Another object of the invention is the provision of a former which is simple and effi-

cient in construction, which may be placed in and removed from a shoe expeditiously and without injury thereto.

A further object of the invention is the 60 provision of a former capable of adjustment to fit various sized shoes, and provided with means whereby the longitudinal pressure of the former upon the shoe may be regulated to suit varying conditions. Other objects 65 of the invention will be more specifically described and pointed out hereinafter.

My invention contemplates a former adapted for insertion in a shoe and provided with expanding means, whereby pressure is 70 exerted longitudinally upon the front and rear portions of the shoe to straighten it and to cause the sides to close in. Preferably the pressure is exerted in a plane which passes longitudinally and centrally through 75 the shoe, and is approximately perpendicular to the sole. In its preferred form my invention contemplates a former comprising two over-lapping members connected together, but capable of relative sliding movement, one upon the other, with expanding 80 means between; one of said members being adapted to engage the rear portion of the shoe on a central line from the sole to the top of the upper, and the other of said members being adapted to engage the toe and the front of the vamp or upper of the shoe 85 on a central line.

One of the important features of my invention resides in providing expanding 90 means which is resilient and adjustable, whereby the former may be easily adapted to different sizes and kinds of shoes to secure the best results under different and varying conditions. It is important that the shoe 95 be kept under the proper tension during the final processes of manufacturing to avoid stretching the leather or warping the shoe; and since the amount of tension will vary within certain limits to conform to varying 100 conditions of stock, it is essential to the securing of satisfactory results that the expanding means be resilient and adjustable. Furthermore, the provision of such means permits the former to be inserted in and removed from the shoe without injury thereto, and without changing or modifying the correct lines given it by the former.

In the drawings illustrating the preferred 110 form of my invention, Figure 1 is a side elevation of a former constructed and operated in accordance with my invention, with

the outline of an oxford shoe shown in dash lines, in order to illustrate the operative position of the former within the shoe. Figure 2 is a side elevation of an extension, adapted to be mounted upon the former shown in Figure 1, in order to adapt it for use in bal or high shoes.

In the drawings illustrating one embodiment of my invention, there is shown a former made up of two main members,— a heel member 10 and a toe member 12, which members are interlocked to prevent separation, yet are capable of a sliding movement, one in relation to the other, in a longitudinal direction whereby the former may be expanded or contracted longitudinally. These two members may be of any suitable form or construction, but preferably are made of stiff wire, which conduces to a low cost of construction and at the same time reduces the weight of the device without affecting its efficiency.

The heel member 10 is formed at its forward end into a circular loop 14, in which is loosely mounted the toe member 12; the rear portion of the heel member 10 being bent upwardly and then downwardly to form a heel piece 16. If desired, the downward loop of the heel piece 16 may be fastened to the upward loop at 18 by solder or in any other suitable manner. The toe member 12 may be provided with a rounded forward end, such for instance, as the ball 20 screwed thereon, in order to prevent injury to the toe portion of the shoe, and at its rear end may be bent substantially at a right angle and provided with a loop 22 to enclose loosely the heel member 10. These two members are, through the loops 14 and 22, permanently secured together against separation, although each is free to be moved in a longitudinal direction in relation to the other member.

To hold the former in an extended position, any suitable means may be interposed between the two members to force them apart longitudinally, or, in other words, to extend the former in that direction, and one such means is shown in the drawings, comprising a helical spring 24, mounted on the heel member 10, and abutting at one end the loop 22 of the toe member 12 and at the other end a block 26, mounted on the member 10 and adapted to be held in any adjusted position by a set screw 28.

If desired, the member 10 may be provided with suitable graduations 30, to designate the proper location of the block 26 for different sized shoes; these graduations, however, to be based upon a certain normal pressure desired, but in actual use the pressure may be increased or decreased as desired in respect to certain shoes by changing the location of the block 26.

The toe member 12 may be provided with means for retracting it in relation to the heel member 10, such for instance as a finger piece 32, secured to the toe member 12 at 34 by solder or other suitable means; 70 the finger piece preferably having a down loop 36, adapted to enclose the heel member 10 for the purpose of guiding it and rendering it more stable.

I further provide a vamp or cone member 40, adapted to engage the upper portion of the vamp or cone of the shoe; the lower end of this member being in the form of a loop 42 loosely encircling the member 12, and the other portion 44 extending 80 downwardly and having its lower end formed in an elongated loop 46, including both the member 10 and the member 12; the upper end 48 being curled about the portion 44. To hold the vamp or cone member 40 in forward position, I provide a helical spring 50, mounted upon the member 12 behind the loop 42, abutting said loop at one end and being secured to the enlargement 34 at its other end. The spring 50 holds the vamp or cone member 40 in an advance position, yet permits it to be retracted against the pressure of the spring in mounting the former within the shoe.

In Figure 1, I have shown a former 95 which is adapted for use on oxford shoes; but in Figure 2 is illustrated an attachment adapted to be mounted on the former of Figure 1, to adapt it for use on bal or high shoes. This is merely illustrative, because 100 it is apparent that the former shown in Figure 1 may be adapted for high shoes, either by extending the heel portion 16 and the vamp member 40 upwardly to conform to the configuration of the upper part of a bal shoe, or by providing an extension adapted for attachment thereto. The attachment shown in Figure 2 comprises a member 52, 105 extending upwardly and then downwardly, and having a loop 54 which acts as a spring, so that the end 56 of the member may be inserted in the front part of the top of the shoe to exert an outward pressure thereon. The member 52 may be secured to the heel piece 16 by plates 58, held in engagement 110 with the two sides of the heel piece 16 by a screw 60.

The operation of my device is extremely simple and is as follows: The block 26 is first fixed in position, dependent upon the size of the shoe in which the former is to be placed, which location will secure a normal pressure upon the shoe in a longitudinal direction. In order to place the former in the shoe, the finger piece 32 is pulled back, compressing the spring 24, and while in this position the former is inserted in the shoe with the ball 20 in the toe of the shoe, the heel piece 16 in the heel of the shoe, and the finger piece then released. The pressure of 130

the spring 24 causes the member 12 to be moved forwardly and the member 10 rearwardly within the shoe, until the toe and heel are engaged by the respective ends of 5 the former. At the same time the vamp member 40 engages the upper part of the vamp, the spring 50 holding the vamp 40 in its forward position, yet permitting it to retract to a certain extent to conform to the 10 longitudinal dimension of the shoe and the resistance offered by the upper portion of the vamp. The position of the former within the shoe is shown in Figure 1.

The effect of the former upon the shoe is 15 that of exerting a stretching pressure on both the front and back of the shoe longitudinally, which naturally causes the sides of the shoe to straighten and close inwardly toward each other, thereby narrowing the 20 shoe. The former is inserted in the shoe immediately after it is removed from the last, and is maintained therein until the shoe is ready to be packed. As a result of the 25 shoe being under tension during the finishing operations, the necessity of ironing, with the consequent shrinking and searing of the pores of the leather, is either entirely obviated or greatly reduced. At the same time, the application of the dressing to the 30 shoe while the leather is under the tension of the former, fills the pores of the skin, and after the former is removed the dressing serves to retain the shoe in its proper form.

To remove the former from the shoe, the 35 member 12 is retracted through the medium of the finger piece 32, which shortens the former and relieves the pressure of the spring 50 upon the vamp member 40, whereupon the former may be easily removed 40 from the shoe without strain, and without disturbing the correct lines of the shoe.

The provision of graduations denoting 45 the proper position of the block 26 for each size of shoe is of importance, since it permits the former to be properly adjusted before insertion in the shoe, and thus saves the time which otherwise would be wasted in various experimental adjustments designed to attain the desired pressure.

50 It will be observed that the adjustable feature of my device gives it a wide range of adaptability, which is a very material consideration when the initial expense of securing an adequate number of devices for a 55 manufacturing business is involved. At the same time, the fact that the device may be made of wire conduces to a low cost, and enables it to be manufactured and sold at a price which will justify its use in large quantities.

60 The advantages attained by the use of my device in the manufacturing and sale of shoes are manifold. It facilitates the handling of the shoe during the final processes; 65 it insures correct and attractive lines in the

shoe when presented for sale, and it improves the fitting qualities. The shoe is given long and narrow lines, and the sides of the shoe hug and fit closely the sides of the foot of the wearer.

70 It is to be understood that my invention is not to be limited to the particular embodiment herein shown and described, as it may be exemplified in various other forms of construction without departing therefrom, all within the scope of the following 75 claims.

What I claim is:—

1. A shoe former having, in combination, 80 a toe member and a heel member in overlapping extensible relation, resilient means for holding said two members in extended relation, said means being adjustable to regulate the amount of pressure exerted thereby when the former is placed in a shoe, 85 a table of graduations marked on said former for regulating the adjustment of said resilient means, a cone member carried by said toe member and resilient means for holding said cone member in forward position.

2. A shoe former having, in combination, 90 a toe member and a heel member in overlapping extensible relation, resilient means for holding said two members in extended relation, said means being adjustable to regulate the amount of pressure exerted by 95 said two members when the former is placed in the shoe, a table of graduations marked on said former for regulating the adjustment of said resilient means, a cone member carried by said toe member for engaging the cone of the shoe on a centre line and resilient means for holding said cone member in forward position to exert pressure upon the 100 cone of the shoe.

3. A shoe former having, in combination, 105 a toe member and a heel member arranged in interlocked overlapping extensible relation, resilient means for holding said two members in longitudinally extended relation, said means being adjustable to regulate the amount of pressure exerted thereby when the former is placed in the shoe, a cone member carried by said toe member, and resilient means for holding said cone member in forward position.

4. A shoe former having, in combination, 110 a toe member and a heel member arranged in interlocked overlapping extensible relation, resilient means for holding said two members in longitudinally extended relation, said means being adjustable to regulate the amount of pressure exerted by said two members when the former is placed in the shoe, a cone member carried by said toe member for engaging the cone of the shoe on a centre line and resilient means for holding said cone member in forward position to exert pressure upon the cone of the shoe.

5. A shoe former having, in combination, a toe member and a heel member in longitudinally overlapping extensible relation, resilient means for holding said two members in extended relation, said means being adjustable to regulate the amount of pressure exerted thereby when the former is placed in the shoe, a table of graduations marked on said former for regulating the adjustment of said resilient means, a cone member carried by said toe member, and resilient means for holding said cone member in forward position.
6. A shoe former having in combination a toe member adapted to engage the toe of a boot or shoe, a heel member adapted to engage the heel portion of a boot or shoe on a central line from the sole to the top of the upper, resilient means for pressing said toe member and said heel member apart to extend the former, said resilient means being adjustable for regulating the pressure exerted thereby, means carried by said toe member for engaging the front portion of the upper of the boot or shoe on a central line, and resilient means for holding said last-mentioned means in an advanced position.
7. A shoe former having, in combination, two members connected together in overlapping sliding relation and adapted when placed in a shoe to engage the shoe on the centre line at the toe and heel and resilient means for forcing said members apart to extend said former and to exert pressure on the shoe longitudinally on a centre line; said resilient means being adjustable for regulating the amount of pressure exerted upon the shoe.
8. A shoe former having, in combination, two members loosely connected together in overlapping sliding relation and adapted when placed in the shoe to engage the shoe on its central axis at the heel and toe and adjustable resilient means for forcing said members apart in a longitudinal direction to extend the same and to stretch the shoe longitudinally; said means comprising a spring mounted on one of said members adapted at one end to abut the other of said members and at its other end to abut a block adjustably arranged on the first of said members.
9. A shoe former having, in combination, two members connected together in overlapping sliding relation adapted when placed in the shoe to engage the shoe on its longitudinal central axis, resilient means for forcing said members apart to stretch the shoe longitudinally, said means being adjustable to regulate the pressure exerted by said two members, a cone member carried by the toe member for engaging the cone of the shoe on a central line and resilient means for holding said cone member in forward position to exert pressure on the cone of the shoe.

In witness whereof, I hereunto set my hand this seventeenth day of April, 1922.

ADELBERT A. DURKEE.
